CLIP SQUEEZING TOOL

Frithiof P. Forss, Aurora, Ill., assignor to Independent Pneumatic Tool Company, Chicago, Ill., a corporation of Delaware

Application January 10, 1944, Serial No. 517,677

8 Claims. (Cl. 140—55)

This invention relates to portable power operated clip squeezing tools.

It has been the practice in fabricating bed springs, seat cushions and similar structures to fasten the coiled springs together at their adjacent portions and to the supporting frame by substantially U-shaped metal clips. These clips heretofore have been applied and clamped about the spring and the supporting wires by the use of manually operable hand tools of the plier type with relatively long shanks or handles to offer the leverage required to deform the clips in clamping them about the adjacent wires. In using these manually operable tools the operator first positions the clip between the jaws of the tool with one hand and while so holding the clip presses the tool handles towards each other by the other hand to grip and support the clip in the jaws of the tool. While still holding the handles under this slight pressure to prevent the clip from being displaced or dropping out of the tool, the operator with the free hand adjusts or draws the adjacent spring or other wires together for entry into the opening in the clip in applying the clip about the wires by the tool. When the clip is positioned about the wires, the operator thereupon squeezes the tool handles together with sufficient force to compress or clamp the clip about the engaged wires for securing them together. As these clips are usually made of metal of different sizes and thicknesses according to the size of the spring and supporting wires to be fastened together, the operator is required to exert a relatively heavy pressure on the tool handles to squeeze the clips in place. Frequently, a pressure as high as several hundred pounds is demanded to squeeze some of these clips together. This heavy pressure is the dominating factor in the use of these manually operable tools and physically strong operators are required to perform this work with the result the fatigue and strain is an element which limits the output in these clip squeezing operations.

This invention is designed to overcome the defects hereinabove noted, and the objects of my invention are to provide a portable power operated tool which is so constructed that it will hold the clip in position by applied power and will allow the operator to manipulate the tool to position the clip over the adjacent portions of the spring or other wires to be joined, and which subsequently allows the operator to cause the tool to apply heavy clamping pressure by power actuated means, thus relieving the operator of all effort of initially holding the clip in place and

of the relatively heavy effort of squeezing the clip to deform it and clamp the adjacent portions of the spring or other wires together.

A further object of my invention is to provide 5 a power operated portable clip squeezing tool which has a main power actuated means for squeezing the clip into clamping relation about the spring or other wires to be joined, and an auxiliary power actuated means for initially holding the clip with sufficient grip to prevent the clip being displaced or dropping out of the tool when applying the clip to the work by the tool, and which tool is so constructed that manually operable means are provided within convenient reach 15 of the operator and forming part of the tool as to successively control the clip gripping and clip squeezing operations, while holding the tool in one hand and positioning or adjusting the spring wires to be engaged by the clip with the other hand without undue fatigue being impressed on the operator in these clip applying and squeezing operations.

A further object of my invention is to provide 20 a portable power operated clip squeezing tool sufficiently small in size and light in weight that the tool may be conveniently gripped and handled by the operator in one hand and which tool has its main power actuated means in the form of a cylinder and a piston assembly to receive a pressure fluid for operating the piston on its power and return strokes for respectively moving the 25 relatively movable jaws or clip engaging members of the tool into clip squeezing positions and allowing said members to be moved into their open positions to receive another clip on the return stroke of the piston, and which tool has its auxiliary power actuated means in the form of a spring which is compressed in the return stroke 30 of the piston and which spring means is made effective to initially move the clip engaging members into gripping relation with the clip for holding the same in the initial movement of the controlling means of the tool by the operator.

In conjunction with the foregoing, my invention 35 contemplates a control means which may be in the form of a single valve unit carried by the tool and which unit is movable by the operator into a first position to move the jaws or clip engaging members into gripping engagement with the clip and subsequently into a second position 40 in the continued movement of the control means to apply pressure fluid on the rear side of the piston for moving the members into clip squeezing 45 relation, the spring functioning on relieving pres-

sure on the front side of the piston in the initial movement of the control means.

The invention consists further in the structural organization and arrangement of parts herein-after described and claimed.

In the accompanying drawings—

Fig. 1 is a longitudinal sectional view with parts in elevation of my improved power operated clip squeezing tool, the power piston being shown at the end of its return stroke;

Fig. 2 is a similar sectional view showing the jaws of the tool moved into holding position with respect to the clip in the initial movement of the piston by a spring means to be hereinafter described;

Fig. 3 is a top plan view of the tool with parts broken away and in section for the purpose of illustration;

Fig. 4 is a view showing a detail of construction with respect to the spring elements for normally moving the jaws into open positions; and

Fig. 5 is a vertical sectional view taken on line 5—5 of Fig. 4.

As shown in the drawings, the clip squeezing tool of my invention comprises a cylinder 1 small enough in diameter to serve as a grip for the tool and mounting a piston 2 secured to the rear end of a piston rod 3 which rod extends through a header 4 screwed into and closing the front end of the cylinder. The rear end of the cylinder 1 is closed by a header structure 5 cast integral with the cylinder and mounting a throttle valve 6 and a threaded fitting 7 for connecting an air hose (not shown) to the tool for supplying compressed air to the cylinder for operation of the piston 2 therein.

The piston rod 3 is provided with an axial bore 8 closed at its front end and opening at its rear end through the rear end on the rod on the rear side of the piston 2 as shown in Fig. 1. Located within the bore 8 is a coiled expansion spring 9 and a plunger 10, the latter being pressed by the spring 9 against the rear header 5 of the cylinder. The plunger 10 has a pin and elongated slot connection 11 and 12, respectively, with the rod to slidably support the plunger within the rod and limit the projection of the plunger from the rod.

A driving head 13 is mounted on the front end of the rod 3 beyond the header 4 and said driving head 13 mounts a pair of rollers 14, 14, one above the other, as shown.

Cast integral with and extending forwardly of the header 4 at the front end of the cylinder 1 is a pair of laterally spaced, substantially parallel bracket arms 15, 15 of equal length. Located between the arms 15 is a pair of jaw members 16, 16 connected to the arms 15 adjacent their outer ends by a fulcrum pin 17 anchored in place as shown herein.

The power applying ends 18, 18 of the jaws 16 are beyond the forward ends of the arms 15 and are shaped to engage a metal clip 19 to be applied by the tool.

The power receiving shank portions 20, 20 of the jaws 16 extend inwardly towards the header 4 and receive between them the driving head 13 and the rollers 14. The rollers 14 act on the opposed cam surfaces 21, 21 of the shank portions 20 of the jaws to pivot the latter about the pin 17 to close their outer ends 18. This action compresses or clamps the clip 19 about the wire or rod members 22, 22 to be connected together by the clip as will be seen from Fig. 2. The jaws 16 in this operation may either bring the ends of

the clip into abutment or into overlapping relation depending on the shape given to the clip engaging ends of the jaws.

Springs 23, 23 supported by the header 4 act 5 on the jaws 16 to pivot the same into open positions on the return stroke of the driving head 13 with the piston 2 to the starting position of the driving head at the rear ends of the jaws as shown in Fig. 1. The springs 23 are anchored by 10 screws or other fasteners 24, 24 to shoulders or ledges 25, 25 on the header 4 and have their loop-shaped body portions 26, 26 between the bracket arms 15 and bearing inward on the jaws 16 to hold them against the rollers 14 and to open the 15 jaws on the return stroke of the piston 2.

The throttle valve 6 is mounted in a bushing 27 fitted in the rear header 5 and comprises two axially movable parts 28, 29. The part 28 is a valve member which is biased to a seat 30 within 20 the bushing by a coiled spring 31 also within the bushing below the valve 28. The air passages 32, 33 in the bushing are above and below the valve seat 30 and respectively connect with the air intake passage 34 at the hose fitting 7 and with the 25 rear end of the cylinder 1 through a port 35 in the header 5 as shown in Figs. 1 and 2.

The part 29 of the throttle valve 6 comprises 30 a stem slidably mounted in the bushing 27 above the part 28 and extends out of the bushing at its upper end to the exterior of the cylinder 1 and is there engaged by one of two interacting valve actuating levers 36, 37. The stem 29 carries a valve member 38 adjacent its upper end and which valve member 38 serves to open and close 35 an exhaust port 39 at the upper end of the bushing 27.

The valve stem 29 is provided with an additional valve member 40 to open and close the side ports 41, 42 in the bushing 27 and which ports 40, 41, 42 respectively connect the bore of the bushing with a channel 43 about the outside of the bushing at the ports 41, 42. This valve 40 fits the bore of the bushing and closes the ports 41, 42 when the parts are in the positions shown in 45 Fig. 2 and opens the ports when the valve is in the position shown in Fig. 1.

The levers 36, 37 are both fulcrumed between webs or lugs 44, 44 on the cylinder 1. Moving 50 the longest lever 37 towards the cylinder 1 actuates the throttle valve 6 to supply air pressure to the rear end of the cylinder for forcing the piston 2 on its forward or power stroke. The springs 31 and 45 move the throttle valve and the levers upwardly when the levers are released 55 as indicated in Fig. 1.

The operation of the tool is as follows:

The parts are in the positions shown in Fig. 1 in the normal position of the tool. The operator 60 grasps the tool about the cylinder 1 with one hand and with the other hand inserts the clip 19 between the open ends 18 of the jaws 16. The clip 19 is located between the jaws with the opening in the clip facing outwardly as shown in Fig. 2. The operator while holding the clip 65 in position between the jaws depresses the lever 37 until its motion is resisted by the stronger spring 31 and the spring 9 thereupon moves the piston to initially move the jaws to grip the clip therebetween. This occurs due to closing 70 off the live air at the valve 40 and opening the front side of the piston 2 to the exhaust 39 and the cylinder passage 46 on unseating the valve 38 as shown in Fig. 2. The spring 9 is only strong enough to move the driving head 13 initially 75 between the shanks 20 of the jaws 16 to grip and

hold the clip between the outer ends 18 of the jaws as shown in Fig. 2. The valve member 28 is seated at this time and live air is cut off to the rear side of the piston 2.

The pressure of the spring 9 holds the clip in the tool and the operator may manipulate the tool to engage the clip about the spring or other wires 22 to be joined as shown in Fig. 2. With the clip held between the jaws by the spring, the tool may be handled without fear of the clip being displaced or dropping out of the jaws and may be extended to any position desired to engage about the selected adjacent portions of the wires to be clamped.

After the clip 19 as supported by the tool is applied about the elements 22, the lever 37 is further depressed towards the cylinder 1 and the stem element 29 of the throttle valve 6 is forced against the valve member 28 to unseat the same and open the ports 32 and 33 to the rear end of the cylinder 1 behind the initially moved piston 2. This results in admitting live air to the near side of the piston 2 and forcing it on its power stroke to carry the driving head 13 further between the shank portions 20 of the jaws and move their outer ends 18 into closing relation to clamp the clip 19 about the wire elements 22.

Releasing the lever 37 following this clip clamping operation, causes the spring 31 to seat the valve 28 and cut off the supply of live air to the rear side of the piston. The valve 38 partially opens the port 35 and connects it through the bushing 27 to the exhaust port 48 for the rear end of the cylinder.

In this outward movement of the lever 37, the spring 45 seats the valve 38 to close the exhaust port 39 and opens the port 47 to the bore of the bushing 27. In this movement, the valve 40 opens the ports 41, 42 and connects the front end of the cylinder to the live air supply. This occurs through the port 32, bushing 27, the ports 41, 42, channel 43, ports 49, 47 in the bushing and cylinder passage 46 as shown in Fig. 1. Hence, the piston 2 is moved by live air pressure on its return stroke and the spring 9 is compressed by the plunger 10 having contact with the rear header 5. The tool is now in position for another clip applying and clamping operation.

The portable power operated clip squeezing tool as herein disclosed has the advantages and purposes before mentioned. The tool is simple in construction and operation and materially increases production without undue operator fatigue in these clip squeezing operations in fabricating bed springs, seat cushions and similar structures.

The details of construction and arrangement of parts shown and described may be variously changed and modified without departing from the spirit and scope of my invention, except as pointed out in the annexed claims.

I claim as my invention:

1. A portable power operated clip squeezing tool of the character described comprising, a support, relatively movable clip squeezing members on the support and having clip engaging portions, a driving element reciprocably mounted on the support for moving said members into clip squeezing and clip engaging positions, respectively, on the power stroke of said element, power actuated means on the support for reciprocating said element, spring means on the support for initiating the power stroke of said element for initially moving said members to grip and support the

clip in advance of the movement of the element by the power actuated means to squeeze the clip by said members, said spring means being compressed on the return stroke of the driving element for storing energy for a subsequent clip gripping operation, and control means for successively controlling at the will of the operator the operation of said spring means and said power actuated means.

10 2. A portable power operated clip squeezing tool of the character described comprising, a support, relatively movable clip squeezing members on the support and having clip engaging portions, power actuated means on the support for

15 moving said members into closing relation for squeezing the clip engaged thereby, control means on the support for controlling the application of power to said power actuated means, and spring means operable in response to the initial movement of the controlling means for moving the members into holding relation with the clip for supporting the same in advance of the application of power to said power actuated means to squeeze the clip by said members.

20 25 3. A portable power operated clip squeezing tool of the character described comprising, a support including a cylinder, relatively movable clip squeezing members on the support and having clip engaging portions, a piston and piston rod assembly reciprocably mounted in said cylinder for moving said members into clip squeezing and clip gripping positions, respectively, valve means on the support for controlling the admission and exhaust of a pressure fluid to the opposite sides

30 35 of the piston for reciprocating the same on its power and return strokes, and means operable on exhausting the front side of the piston by the valve for initially moving the members into gripping engagement with the clip for supporting the same in advance of admitting pressure fluid to the rear side of the piston for driving the same on its power stroke to squeeze the clip by said members.

40 45 4. A portable power operated clip squeezing tool of the character described comprising, a support including a cylinder, relatively movable clip squeezing members on the support and having clip engaging portions, a piston and piston rod assembly reciprocably mounted in said cylinder for moving said members into clip squeezing and clip gripping positions, respectively, valve means on the support for controlling the admission and exhaust of pressure fluid to the opposite sides of the piston for reciprocating the same on its power

50 55 return strokes, and spring means carried by the rod and automatically compressed in response to the return stroke of the piston for initially moving said members to grip and support the clip in advance of admitting the pressure fluid to the rear side of the piston to move the same on its power stroke to squeeze the clip by said members.

60 65 70 75 5. A portable power operated clip squeezing tool of the character described comprising, a cylinder having front and rear headers closing the opposite ends of the cylinder, relatively movable clip squeezing members supported upon the cylinder and having clip engaging portions, a piston and piston rod assembly reciprocably mounted in said cylinder and operable on said members for moving the same into clip squeezing and clip gripping positions, respectively, valve means for controlling the admission and exhaust of a pressure fluid to the opposite sides of the piston for reciprocating the same on its power and return

strokes, a spring, and a co-acting plunger, both mounted in the rod, said plunger engaging the rear header for compressing the spring in response to the return stroke of the piston, said spring becoming effective on the release of pressure from the front side of the piston by the valve for initially moving the members into gripping relation with the clip for supporting the same in advance of admitting pressure fluid to the rear side of the piston for driving the same on its power stroke to squeeze the clip by said members.

6. A portable power operated clip squeezing tool of the character described comprising, a support, relatively movable clip squeezing members on the support and having clip engaging portions, a pressure fluid actuated motor on the support for moving said members into closing relation for squeezing the clip engaged thereby, valve means on the support for controlling the admission and exhaust of a pressure fluid to said motor, and means operable in the initial movement of the valve means for moving the members into gripping relation to the clip for supporting the same in advance of admitting pressure fluid to the motor for squeezing the clip by said members, said valve having continued movement in one direction to successively control at the will of the operator said clip gripping and clip squeezing operations.

7. A portable power operated clip squeezing tool of the character described comprising, a support, relatively movable clip squeezing members on the support and having clip engaging portions, power actuated means on the support and having power and return strokes with respect to said members, said power actuated means serving

in its power stroke to initially move said members to grip and support the clip engaged thereby and thereafter squeeze the clip engaged between said members, control means for controlling the power and the return strokes of said power actuated means and for successively moving at the will of the operator said means into said clip gripping and squeezing positions, respectively, and means on the support for holding the members in operative relation to said power actuated means and for moving the members into open positions on the return stroke of said power actuated means to release and receive a clip with respect to said members.

8. A portable operated clip squeezing tool of the character described comprising, a support, relatively movable clip squeezing members on the support and having clip engaging portions, a reciprocable driving element on the support and having power and return strokes with respect to said members, power actuated means on the support for reciprocating said driving element, spring means on the support for imparting initial movement to the driving element in response to its power stroke for moving said members to grip and hold a clip in advance of squeezing the clip engaged by said members, control means for controlling at the will of the operator the operation of said power actuated and spring means, and means for holding said members in contact with said driving element and for moving the members into open positions on the return stroke of said driving element to release and receive a clip with respect to said members.

FRITHIOF P. FORSS.
